Patented Apr. 6, 1965

200,803

PUNCHING MACHINE

Rocco L. Stefano, Williamsville, Ralph L. Weisbeck,
Cheektowaga, and Joseph W. Shingler, North Tonawanda, N.Y., assignors to Punch Products Corporation, Buffalo, N.Y., a corporation of New York

Filed Feb. 27, 1964, Ser. No. 78,810

Term of patent 14 years

(C. D55—1)

FIG. 1

Des. 200,803

PAGE 2

FIG. 2

FIG. 4

FIG. 3

FIG. 1 is a top planar view of a punching machine embodying our new design;

FIG. 2 is a front elevational view of our punching machine;

FIG. 3 is a right-hand end elevational view of FIGS. 1 and 2; and

FIG. 4 is a left-hand end elevational view of FIGS. 1 and 2.

The side opposite that shown in FIG. 2 is flat and unornamented.

We claim:

The ornamental design for a punching machine, substantially as shown and described.
